(57) **CLAIM**

The ornamental design for a dining table, as shown and described.

DESCRIPTION

FIG. 1 is a perspective view of a dining table showing my new design;

FIG. 2 is a front elevational view, the opposite side being a mirror image thereof;

FIG. 3 is an end elevational view, the opposite end being a mirror image thereof; and,

FIG. 4 is a top view thereof.

The views of the dining table not shown form no part of the claimed design. The separation and bracket indicate, for ease of illustration, that the precise length of the dining table is not claimed. The broken lines depicting feet and carvings on the pedestals represent environmental elements only and form no part of the claimed design.
